HOPPER DOOR FOR RAILWAY CARS

Original Filed Aug. 10, 1925

Inventor:
Clinton E. Sisson

UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

HOPPER DOOR FOR RAILWAY CARS.

Original application filed August 10, 1925, Serial No. 49,295. Divided and this application filed March 8, 1926. Serial No. 93,588.

The invention relates to a railway dump car having a "door" forming a part of the car for retaining the load therein which door is provided with hinges adjacent one of its edges and is capable of being "dropped" or swung open so that the load in discharging slides or passes over the upper surface of the door. Any means of raising the door to the closed position and any means for locking 10 and releasing the door may be employed with my device.

Experience has shown that a slight projection on the upper surface of such a door causes the discharging load to bank up and seriously retard the unloading of the car sometimes completely obstructing the opening and at other times causing some of the material to remain in the car. It is essential 15 that the entire load be discharged when the doors are dropped in order to conserve time when the cars are being used to ballast a main line track, or to eliminate the necessity of maintaining men to remove any small portion of the load that remains in the car 20 after the doors are dropped.

The relative position of the rail, the truck (and other parts of the car) and service conditions also regulate the inclination of the door after it is dropped, so that it is seldom 25 possible to allow the doors to drop to a vertical position; in fact, in a drop bottom gondola car, the doors are positioned only about thirty (30) degrees from a horizontal plane when in open position.

30 A door for this purpose must be very strong and durable because:

First, it is a part of the floor of the car and as such must sustain the load as well as the impact blow of the load when the car is 35 in motion. Second, the car is frequently loaded from chutes or tipples from a height of ten feet or more, causing the load to be dropped directly upon the doors. Third, clam shell buckets are frequently used to unload 40 such cars and it is not uncommon for these buckets to rest upon and drag over the doors. Fourth, when the door suddenly comes to rest after being dropped, it is not only subjected to a severe shock, but it must 45 sustain the severe impact thrust of the load which, of course, follows the door. Fifth, as the load is theoretically equally distribut-

ed, the door must be strong over its entire area and must be capable of transmitting the resulting stresses to the car body without 55 much deflection and no substantial distortion. Any bending of the door or drooping of the corners would cause a leak of the lading especially of such fine material as sand, chats, etc. Any bending or warping might 60 interfere with the complete closing and locking of the door.

As it costs as much to haul a ton of car as it does to haul a ton of paying freight, it is imperative that the car and any part 65 thereof be as light as possible. Furthermore, the total weight of the car and freight is determined by the strength of certain standard axles, so that the lighter the car the greater amount of freight a given car will be 70 allowed to carry.

Various means have been used to strengthen a plate metal door to meet the service conditions. Reinforcements have been secured to the door thus materially increasing its 75 weight, which is objectionable. Various integral reinforcements (such as corrugations) have been formed in metallic plates which, however interfere with the discharge of the loading or have other objectionable features. 80

In my design the corrugations are beams supported adjacent their opposite ends by the hinges or hinge strap positioned substantially at right angles to the corrugations. The hinge-beams are supported at their opposite ends to the car body. This cross work 85 of beams makes a very strong and efficient means of carrying the load. Continuous beams supported adjacent their opposite ends have great strength to resist the stresses of equally distributed loads. In my arrangement, I have obtained cooperation of the corrugations and hinges and yet have not interfered with the discharge of the lading. 90 This last feature is accomplished by the peculiar and particular configuration of the corrugation.

One of the objects of the invention is to obtain a strong durable door for a load discharging freight car made of a metallic plate 95 formed with integral corrugations which are positioned approximately normal to the direction of discharge of the lading but are of such configuration as not to interfere with

the movement of the cargo when leaving the car.

Another object of the invention is to provide an arrangement whereby the corrugations are positioned substantially normal to the supporting hinges and yet will not interfere with the discharge of the lading.

Another object of the invention is to attach the hinges to the corrugated door so that the securing means (usually rivets) will not interfere with the discharging of the cargo.

Another object of the invention is to obtain a door reinforced by corrugations which strengthen the entire area of the door which supports the load.

The advantages of my door are applicable to any door of a freight car, such as drop bottom general service cars, (used in the drawings), hopper cars, swinging side doors or hopper bottom coal cars, etc.

For convenience of illustration and ease of description, straight lines have been used to show the corrugations. However, it is understood that curves or a series of curves may be used and still come within the scope of the invention.

In the drawings:

Fig. 1 shows a portion of a railway car with my device applied thereto.

Fig. 2 is a section on line 2—2 of Fig. 1.

Fig. 3 is similar to Fig. 2 but shows the door in open position.

Fig. 4 is a section on line 4—4 of Fig. 1.

Fig. 5 is an enlarged section of the corrugation.

Fig. 6 shows the attachment of the hinge to the door.

To illustrate one adaptation of my device, I have shown a so-called "general service" drop bottom gondola car wherein the major portion of the floor consists of drop doors. The door openings are surrounded by the center construction, side wall and cross diaphragms. In normal or closed position the door completely closes this opening and, in fact, is a trifle larger on all sides than the opening so as to provide a lap joint between the door and the car frame members. The hinge beams are hinged to the center construction and are supported adjacent the side wall by the raising or locking mechanisms. Any convenient stop, such as 2, may be used to limit the downward movement of the door.

The door is made of a metallic plate (preferably steel) which is reinforced with integral corrugations 3 resting upon hinge beams 4, the corrugations extending continuously their full depth between the hinges and then decreasing in depth (5) and merging into the original plane of the plate 6 and preferably in close proximity to the stiffening flanges 7, which are formed at the opposite edges of the door. This arrangement

provides a very efficient double supported beam with overhanging end portions and obtains a cooperation between the hinge beams, the corrugations and the flanges.

These corrugations extend continuously between the opposite edges of the door and preferably under the adjacent cross diaphragms 9 (forming the opposite edges of the door opening) as shown in Fig. 4, so as to reinforce the entire part of the door upon which the cargo rests.

The contour of the corrugations is such that when the doors are in open or dropped position the corrugations will not interfere with the discharge of the lading. For convenience, I have described the corrugations as comprising an inner wall 30 and an outer wall 31, i. e., the inner wall is the one positioned near the inside edge or hinge edge of the door. The inner walls are preferably substantially perpendicular to the original plane of the plate 6, so as to form stiff and strong ribs. The outer walls are preferably wider and positioned obliquely to the original plane of the plate. The obliquity is such that when the doors are open these walls are inclined toward the outer edge of the door, i. e., the angle or slant of the plate of the outer walls (as shown by line 12—12) will not permit the lading to stay thereon, and furthermore, the outer wall chutes the cargo over the inner wall or web of the adjacent corrugations so that the inner wall does not retard the movement of the cargo.

The inner walls 30 and outer walls 31 merge into each other and there is no space between the corrugations. The inner walls are substantially perpendicular to the plane of the plate so as to form stiff webs, while the outer walls are wider and positioned obliquely to the original plane of the plate. The hinge 4 is preferably joggled and secured to the outer walls 31 adjacent the inner walls, as shown in Fig. 6, so that the discharging material will not come in contact with the rivets or bolts for reasons outlined above.

This is a division of my co-pending application Serial No. 49,295, filed August 10, 1925.

I claim:

1. In combination with the other elements of a railway dump car; a door made of a metallic plate formed with corrugations, each of said corrugations comprising an inner wall and an outer wall, said inner wall being narrower than said outer wall, and substantially perpendicular to the original plane of the plate.

2. In combination with the other elements of a railway dump car; a door made of a metallic plate formed with corrugations terminating within the edges of the plate, each of said corrugations comprising an inner wall and an outer wall, said inner wall be-

ing narrower than said outer wall, and substantially perpendicular to the original plane of the plate.

3. In combination with the other elements of a railway dump car; a door made of a metallic plate formed with a plurality of contiguous corrugations, each of said corrugations comprising an inner wall and an outer wall, said inner wall being narrower than said outer wall, and substantially perpendicular to the original plane of the plate.

4. A door for a railway car made of a metallic plate formed with corrugations, each of said corrugations comprising an inner wall and an outer wall, said inner wall being narrower than said outer wall, and substantially perpendicular to the original plane of the plate.

5. In combination with the other elements of a railway dump car; a door made of a metallic plate formed with corrugations comprising inner and outer walls, the outer walls being of such angular relation to the original plane of the plate that when the door is in open position said outer walls are

inclined toward the outer edge of the door, said inner walls being substantially perpendicular to the original plane of the plate.

6. In combination with the other elements of a railway dump car; a door made of a metallic plate formed with corrugations comprising inner and outer walls, the inner walls being substantially perpendicular to the original plane of the plate, the outer walls being positioned obliquely to the original plane of the plate, and hinges attached to the car body extending normal to said corrugations and secured to said outer wall.

7. In combination with the other elements of a railway dump car; a door made of a metallic plate formed with corrugations comprising inner and outer walls, the inner walls being substantially perpendicular to the original plane of the plate, the outer walls being positioned obliquely to the original plane of the plate, and hinges attached to the car body extending normal to said corrugations and secured to said outer wall adjacent said inner wall.

VINTON E. SISSON.
